UNITED STATES PATENT OFFICE.

GIOVANNI BOSCARRELLI, OF PIACENZA, ITALY.

ROLLING-MILL APPLIANCE.

Application filed May 12, 1924. Serial No. 712,887.

This invention relates to improvements in rolling mill appliances and has for its object an apparatus of the kind used for lifting rolled bars and sheets from the position in which they come through the rolls to the top of the upper roll where they are taken back to the front of the rolls by the "roller" to be re-rolled if required, and adapted to clear on the down-stroke any sheets which 10 may have been rolled during the up-stroke.

The apparatus is operated by compressed air or other pressure fluid and is controlled by the "roller" no "catcher" being required, and only one man is necessary to carry out 15 the rolling process. Such operations of the apparatus as are essential during the cycle are performed automatically, only the rising and clearing actions being manually controlled.

20 Shortly described the apparatus comprises a pair of lifting bars positioned adjacent to the rear of the rolls, a pressure fluid operated cylinder for lifting the bars through mechanism which guides the bars so that they 25 engage the rolled sheets however small their dimensions in the direction of rolling, clear the upper rolls but move forward so that the lifted sheets are held well over the roll in the position for delivery, and mechanism 30 operated by pressure fluid operated cylinder for moving the lifting bars apart before the commencement of the down-stroke to clear sheets which may have come through the rolls and to bring the bars inwards again 35 at the end of the stroke so that they lift the sheets on the next lift. The operator is provided with two foot valves. The first one on being operated causes the bars to rise. The second one on being operated 40 causes the bars to move apart and when this action is finished the bars automatically descend and at the bottom of the stroke automatically move inwards into position for the next lift.

45 A constructional example of the invention is shown in the accompanying drawings, in which—

Figure 1 is a side view of the apparatus.

50 Figure 2 is a plan view of Figure 1, certain details being removed in these two figures for the sake of clearness.

Figure 3 is a fragmentary sectional end view of the automatic valves and operating means taken on the line A—A of Figure 1, and

55 Figures 4, 5 and 6 are detail views at va-

rious points in the operating cycle, of the mechanism for controlling the motion of the lifting bars so that they engage the rolled sheets however small their dimension 60 in the direction of rolling, clear the upper roll and then move well over the upper roll to the position for delivery.

Owing to the size and disposition of the various parts, no main framework is provided in the construction illustrated; the pivots at the fixed points are simply carried in brackets bolted to foundations prepared at suitable positions and levels in the mill building. The whole apparatus is positioned behind the rolling mill indicated diagrammatically by the rolls 1 and 2 and the table 3 onto which the rolled sheets pass. The lifting bars 4 are each slidably mounted on a pair of guide rods 5 secured in a 75 frame 6. A pair of links 7 are pivoted to the rear end of the frame 6 and to brackets 8 secured on suitable foundations. In front the frame 6 is pivoted at 12 to the piston rod 9 of a pneumatic cylinder 10 by which the frame 6 and bars 4 are lifted. The cylinder 10 is pivoted at its lower end to a fixed bracket 11 on a suitable foundation. The path of the point 12 is determined by mechanism shown in detail in Figures 4, 5 and 6, 80 to which reference is directed. A long lever 13 is pivoted to a fixed bracket 14. The pivot pin 15 is secured in the bracket 14 so that it cannot rotate. A short lever 16 is pivoted to the outer end of the lever 13, the 85 pivot pin 17 being keyed to the lever 16. The lever 13 has pivoted to it a trigger 18 adapted to co-act with a slot 19 in the pin 15, and a trigger 20 adapted to co-act with a slot 21 in the pin 17. The trigger 18 is 90 provided with a tension spring 22 (Figure 1) tending to keep it in engagement with the slot 19 and the trigger 20 with a compression spring 23 tending to keep it in engagement with the slot 21. A fixed stop 24 95 is provided on which the lever 13 rests in the lowest position and which holds the trigger 20 out of action. In the lowest position 100 the parts are in the positions shown in Figures 1 and 4, and the lifting bars are sufficiently close to the lower roll 1 to engage the sheets however small their dimensions in the direction of rolling. When the lift commences the long lever 13 is locked by the trigger 18 but the short lever 16 is free.

110 This lever consequently rotates carrying its pivot 17 round and the pivot 12 moves up

and to the right, thus causing the front ends of the lifting bars 4 to follow the first part A. B. of their path indicated by the chain line in Figure 1, thus clearing the upper roll 2.

When the lever 16 arrives at the position shown in Figure 5 its end comes into engagement with the trigger 18 and moves it out of engagement with the slot 19 thus 10 freeing the lever 13, which commences to rise. This action lifts the lever 13 and trigger 20 off the stop 24 so that the trigger 20 engages the slot 21 and locks the lever 16 as shown in Figure 6. The parts remain in this 15 relative position during the rest of the lift so that the pivot 12 rotates about the pivot 15 in bracket 14. The lifting bars 4 therefore move forward during the remainder of the lift so that their front ends follow the 20 second part B. C. of the path indicated in chain lines in Figure 1, thus finishing well over the upper roll so that the lifted sheets can readily be taken by the "roller" who stands on the other side of the mill. On the 25 down-stroke the parts go through the same cycle and the bars 4 follow the same path, in the reverse direction.

The lifting bars 4 are moved apart and inwards by the action of a second pneumatic cylinder 25 carried in the frame 6. The piston rod 26 of this cylinder 25 carries a cross head 27, adjustable by means of nuts 28, having a pin 29 projecting into slots in a pair of three-armed levers 30 pivoted to 30 the frame 6. The levers 30 are each connected to the lifting bars 4 by links 31 and 32, the centres and sizes of the parts being designed to give a proper parallel motion to the lifting bars 4 on an in or out stroke 35 of the cross-head 27. The cylinders 10 and 25 are controlled in the following manner: A foot operated valve 36 is provided in the floor 37 on the "roller's" side of the mill which, when depressed, causes the up-stroke 40 of the cylinder 10. A second foot valve 38 adjacent to the valve 36 when depressed causes an out-stroke of the cylinder 25 thus moving the lifting bars 4 apart. When the 45 lifting bars 4 are in the raised position and have moved into the outward position, the face of a plate 31 in one of the lifting bars 50 engages and operates a valve 40 carried on a bracket 3, this causing the cylinder 10 to effect the downstroke. The plate 39 is 55 shaped to remain in contact with the valve 40 during the downstroke till the bottom of the stroke when the plate just clears the valve, thus releasing it as shown in Figure 3. At the end of the downstroke a projection 33 60 on the plate 39 depresses a valve 34 which causes the cylinder 25 to make the in-stroke thus closing the lifting bars towards one another. At the end of this action the projection 33 is just clear of, and releases the 65 valve 34. It will be seen that four valves

are provided for controlling the four movements of the cylinder 10 and 25, two 36 and 38, manually operated respectively for raising the bars and moving them apart and two 40 and 34 automatically operated respectively to lower the bars and close the rods inwardly. Owing to the method of carrying the operating members 39, 33 on the lifting bars, the valve 40 is not operated during the upstroke and the valve 34 is only 70 operated when the bars are in the lowest position, so that no interference between the controls is produced.

The apparatus is operated in the following manner: The "roller" passes the required number of bars or sheets through the mill and they rest on the table 3. When the desired number have accumulated, he depresses the valve 36 thus effecting an up-stroke. The lifting bars 4 being in the position when they are nearest together, engage the plates and lift them to the top position shown in the chain lines in Figure 1, where they are taken back by the "roller." During the up-stroke as soon as the bars 4 have 80 lifted the sheets clear of the table 3, more sheets may be rolled. When the sheets have been taken back over the rolls from the lifting bars, the "roller" depresses the valve 38. This causes the bars to move apart and when 85 they have moved apart the full distance, the valve 32 is automatically operated and the down-stroke is made, the bars 4 clearing the sheets on the table 3 owing to their separated position. As soon as the end of 90 the down-stroke is reached, the valve 32 is released and the valve 34 automatically operated thus moving the bars 4 towards one another into the position where they will engage the sheets on the next lift. At the end 95 of this action the valve 34 is released, thus leaving all the parts at rest and ready for another lift.

What I claim is:—

1. Apparatus for use in rolling mills for 110 lifting rolled bars and adapted to clear on the down-stroke sheets rolled during the up-stroke, comprising a pair of lifting bars, means including a pressure fluid operated cylinder for lifting and lowering said lifting bars and means for moving said lifting bars apart and towards one another.

2. Apparatus for use in rolling mills for 115 lifting rolled bars and adapted to clear on the down-stroke sheets rolled during the up-stroke, comprising a pair of lifting bars, means for lifting and lowering said lifting bars and means including a pressure fluid operated cylinder for moving said lifting bars apart and towards one another.

3. Apparatus for use in rolling mills for 120 lifting rolled bars and adapted to clear on the down-stroke sheets rolled during the up-stroke comprising a pair of lifting bars, means including a pressure fluid operated 125

cylinder for lifting and lowering said lifting bars and means including a pressure fluid operated cylinder for moving said lifting bars apart and towards one another.

5 4. Apparatus for use in rolling mills for lifting rolled bars and adapted to clear on the down-stroke sheets rolled during the up-stroke comprising a pair of lifting bars, means including a pressure fluid operated 10 cylinder for lifting and lowering said lifting bars along a path such that they engage the rolled sheets however small their dimensions in the direction of rolling clear the upper roll but move well over the upper roll 15 in the lifted position and means for moving said lifting bars apart and towards one another.

5 5. Apparatus for use in rolling mills for lifting rolled bars and adapted to clear on the down-stroke sheets rolled during the up-stroke comprising a pair of lifting bars, means for lifting and lowering said lifting bars along a path such that they engage the rolled sheets however small their dimensions 20 in the direction of rolling clear the upper roll but move well over the upper roll in the lifted position and means including a pressure fluid operated cylinder for moving said lifting bars apart and towards one another.

30 6. Apparatus for use in rolling mills for lifting rolled bars and adapted to clear on the down-stroke sheets rolled during the up-stroke comprising a pair of lifting bars, means including a pressure fluid operated 35 cylinder for lifting and lowering said lifting bars along a path such that they engage the rolled sheets however small their dimensions in the direction of rolling clear the upper roll but move well over the upper roll in the lifted position and means including a pressure fluid operated cylinder for moving said lifting bars apart and towards one another.

45 7. Apparatus for use in rolling mills for lifting rolled bars and adapted to clear on the down-stroke sheets rolled during the up-stroke comprising a pair of lifting bars, manually controlled means for lifting said bars, independently manually controlled 50 means for moving said lifting bars apart and automatic means for lowering said lifting bars when they have moved apart and for moving them towards one another when they have reached the lowest position.

55 8. Apparatus for use in rolling mills for lifting rolled bars and adapted to clear on the down-stroke sheets rolled during the up-stroke comprising a pair of lifting bars, manually controlled means for lifting said 60 bars along a path such that they engage the rolled sheets however small their dimensions in the direction of rolling clear the upper roll but move well over the upper roll in the lifted position, independently 65 manually controlled means for moving said

lifting bars apart and automatic means for lowering said lifting bars when they have moved apart and for moving them towards one another when they have reached the lowest position.

59 9. Apparatus for use in rolling mills for lifting rolled bars and adapted to clear on the down-stroke sheets rolled during the up-stroke comprising a pair of lifting bars, means including a pressure fluid operated 75 cylinder for lifting and lowering said bars along a path such that they engage the rolled sheets however small their dimensions in the direction of rolling clear the upper roll but move well over the upper roll in 80 the lifted position, manually operated means for controlling the lifting action of said cylinder, manually controlled means for moving said lifting bars apart and automatic means for controlling the lowering action of 85 said cylinder when said lifting bars have moved apart and for moving them towards one another when they have reached the lowest position.

90 10. Apparatus for use in rolling mills for lifting rolled bars and adapted to clear on the down-stroke sheets rolled during the up-stroke comprising a pair of lifting bars, manually controlled means for lifting said 95 bars along a path such that they engage the rolled sheets however small their dimensions in the direction of rolling clear the upper roll but move well over the upper roll in the lifted position, means including a pressure fluid operated cylinder for moving said lifting bars apart and towards one another, manually operated means for controlling said cylinder to move said lifting bars apart and automatic means for lowering said lifting bars when they have moved 105 apart and for controlling said cylinder to move them towards one another when they have reached the lowest position.

110 11. Apparatus for use in rolling mills for lifting rolled bars and adapted to clear on the down-stroke sheets rolled during the up-stroke comprising a pair of lifting bars, means including a pressure fluid operated cylinder for lifting and lowering said lifting bars along a path such that they engage the rolled sheets however narrow clear the upper roll but move well over the upper roll in the lifted position, manually operated 115 means for controlling the lifting action of said cylinder, means including a second pressure fluid operated cylinder for moving said lifting bars apart and towards one another, manually operated means for controlling said second cylinder to move said lifting bars apart, automatic means for effecting the lowering action of said cylinder when said lifting bars have been moved apart and for controlling said second cylinder to move said lifting bars towards one another when they have reached the lowest position.

12. Apparatus for use in rolling mills for lifting rolled bars and adapted to clear on the down-stroke sheets rolled during the up-stroke comprising a frame, a pair of lifting bars slidably carried on said frame, a pneumatic cylinder pivotally supported on a fixed bracket below said frame, a long lever pivoted to a fixed bracket in front of said cylinder, a short lever pivoted to said long lever behind said cylinder, a pivot connection between the piston rod of said cylinder, said frame and the free end of said short lever, a spring loaded trigger pivoted on said long lever for locking it when in the lowest position, an arm on said trigger adapted to be engaged by said short lever at the end of its movement to release said trigger, a second spring loaded trigger pivoted on said long lever for locking said short lever, a stop for supporting said long lever in the lowest position and for withdrawing said second trigger in this position, links pivoted to fixed brackets and to the rear of said frame, valves for operating said cylinder, and means for moving said lifting bars apart and towards one another.
13. Apparatus for use in rolling mills for lifting rolled bars and adapted to clear on the down-stroke sheets rolled during the up-stroke comprising a frame, a pair of lifting bars slidably carried on said frame, means for lifting and lowering said frame, a pneumatic cylinder carried in said frame, a pair of three-armed levers pivotally carried in said frame, a cross-head on the piston rod of said cylinder in operative connection with said levers, links on each of said levers connected to each of said lifting bars and valves for controlling said cylinder.
14. Apparatus for use in rolling mills for lifting rolled bars and adapted to clear on the down-stroke sheets rolled during the up-stroke comprising a frame, a pair of lifting bars slidably carried on said frame, a pneumatic cylinder pivotally supported on a fixed bracket below said frame, a long lever pivoted to a fixed bracket in front of said cylinder, a short lever pivoted to said long lever behind said cylinder, a pivot connection between the piston rod of said cylinder, said frame and the free end of said short lever, a spring loaded trigger pivoted on said long lever for locking it when in the lowest position, an arm on said trigger adapted to be engaged by said short lever at the end of its movement to release said trigger, a second spring loaded trigger pivoted on said long lever for locking said short lever, a stop for supporting said long lever in the lowest position and for withdrawing said second trigger in this position, links pivoted to fixed brackets to the rear of said frame, a second pneumatic cylinder carried in said frame, a pair of three-armed levers pivotally carried in said frame, a cross-head on the piston rod of said second cylinder in operative connection with said levers, links on each of said levers connected to each of said lifting bars, a foot valve for controlling said second cylinder.
15. Apparatus for use in rolling mills for lifting rolled bars and adapted to clear on the down-stroke sheets rolled during the up-stroke comprising a frame, a pair of lifting bars slidably carried on said frame, means including a pneumatic cylinder for lifting and lowering said frame, means including a second pneumatic cylinder carried in said frame for moving said lifting bars apart and towards one another, a foot valve for controlling the lifting action of said cylinder, a foot valve for controlling said second cylinder to effect the movement of said bars apart, a valve adjacent to one of said lifting bars for controlling the lowering action of said cylinder, a plate on said lifting bar shaped to engage said valve when said lifting bars have been moved apart and remain in contact with said valve during the automatic lowering caused thereby and release said valve at the end of said lowering action, a projection on said plate, a valve for controlling said second cylinder to move said bars towards one another positioned so as to be operated by said projection in the lowered position of said lifting bars while they are in the apart position and to be released when said bars have moved the full distance towards one another.
16. Apparatus for use in rolling mills for lifting rolled bars and adapted to clear on the down-stroke sheets rolled during the up-stroke comprising a frame, a pair of lifting bars slidably carried on said frame, a pneumatic cylinder pivotally supported on a fixed bracket below said frame, a long lever pivoted to a fixed bracket in front of said cylinder, a short lever pivoted to said long lever behind said cylinder, a pivot connection between the piston rod of said cylinder, said frame and the free end of said short lever, a spring loaded trigger pivoted on said long lever for locking it when in the lowest position, an arm on said trigger adapted to be engaged by said short lever at the end of its movement to release said trigger, a second spring loaded trigger pivoted on said long lever for locking said short lever, a stop for supporting said long lever in the lowest position and for withdrawing said second trigger in this position, links pivoted to fixed brackets to the rear of said frame, a second pneumatic cylinder carried in said frame, a pair of three-armed levers pivotally carried in said frame, a cross-head on the piston rod of said second cylinder in operative connection with said levers, links on each of said levers connected to each of said lifting bars, a foot valve for controlling said second cylinder.

the lifting action of said cylinder, a foot valve for controlling said second cylinder to effect the movement of said bars apart, a valve adjacent to one of said lifting bars for controlling the lowering action of said cylinder, a plate on said lifting bar shaped to engage said valve when said lifting bars have been moved apart and remain in contact with said valve during the automatic lowering caused thereby and release said valve at the end of said lowering action, a projection on said plate, a valve for controlling said second cylinder to move said bars towards one another positioned so as to be operated by said projection in the lowered position of said lifting bars while they are in the apart position and to be released when said bars have moved the full distance towards one another.

In testimony whereof I have signed my name to this specification.

GIOVANNI BOSCARELLI.
